UNITED STATES PATENT OFFICE.

WILLIAM H. MERRILL, OF TAUNTON, MASSACHUSETTS.

HOISTING-BLOCK.

Specification of Letters Patent No. 13,991, dated December 25, 1855.

To all whom it may concern:

Be it known that I, WILLIAM H. MERRILL, of Taunton, in the county of Bristol and State of Massachusetts, have invented a new 5 and useful Improvement in Rolls for Blocks; and I do hereby declare that the following is a full, clear, and exact description of the construction and operation of the same, reference being had to the annexed 10 drawings, making a part of this specification, in which—

Figure 1 is a front elevation of a block with the improvement attached; Fig. 2, a view of one of the rolls; Fig. 3, the step or 15 pintle upon which the roll rests and turns, and Fig. 4, the cap or socket in which the upper end of the roll is supported.

The nature of my improvement consists in so hanging or arranging the rolls that 20 they may be free to rotate.

I make the rolls of any desired metal, iron or brass; the journal or pivot (B. Fig. 2) upon which the roll turns at its upper end is attached to or made with the roll and 25 rotates in a socket or cap, said cap having a hole drilled nearly through it (as shown by the dotted line Fig. 4) to receive the upper journal of the roll. The lower end of the roll, instead of a journal, has a hole (represented by the dotted line Fig. 2) drilled 30 into it, $\frac{1}{4}$ of an inch or more in depth; this hole is to receive the pintle (C. Fig. 3) which is made fast to the block, as is also 35 the cap for the upper end of the roll, by any convenient method, as screws, rivets or bolts. The step or pintle (C. Fig. 3) upon which the lower end of the roll turns, has its upper end or point (D. Fig. 3) made to 40 fit or correspond to the bottom of the hole in the roll. This description of block being

generally used when it is desired to change a perpendicular or an angular to a horizontal line of draft (as is the case in many kinds of hoisting apparatus) and consequently having its position near to or on the surface 45 of the ground, the rolls, as commonly made, (that is, having a journal at each end of the roll and attached to it,) are liable to become clogged or obstructed with dirt—the roll being thus clogged will not turn,— 50 is scored into or woven by the rope, and thus the roll becomes no better than a stationary piece of iron and the benefit resulting from the use of rolls (which is, the prevention of the friction of the rope against 55 the cheeks of the block), is lost—but when hung in the improved manner above described, the roll itself at its lower end, acts as a kind of shield to protect the journal or pintle, so that the roll never becomes 60 clogged, but rotates freely upon the pintle.

The advantage which I claim for my improvement, is, that the cap protecting the upper journal or pintle and the roll, the lower pintle, the dirt or any other obstruction is thus prevented from getting into the 65 bearings and clogging the roll.

I do not claim as my invention the use of friction rolls upon the cheeks of blocks, for 70 these have long been in use; but

What I do claim as my invention and wish to secure by Letters Patent is—

The roll, Fig. 2, the upper socket or cap, Fig. 4 and the lower pintle or step, Fig. 3, used together, for the purposes and in the 75 manner, substantially, as herein set forth.

WM. H. MERRILL.
